COMBINATION TELEPHONE INSTRUMENT AND MEMORANDUM PAD SUPPORT

Lewis B. Simon, Flushing, N. Y.

Application March 9, 1945, Serial No. 127,315

Term of patent 7 years

(Cl. D26—14)

To all whom it may concern:

Be it known that I, Lewis B. Simon, a citizen of the United States, residing at Flushing, Queens Borough, in the county of Queens, city and State of New York, have invented a new, original, and ornamental Design for Combination Telephone Instrument and Memorandum Pad Support, of which the following is a specification, reference being had to the accompanying drawing, forming part thereof.

Fig. 1 is a front perspective view of a combination telephone instrument and memorandum pad support showing my new design; and

Fig. 2 is a rear elevational view thereof.

I claim:

The ornamental design for a combination telephone instrument and memorandum pad support, as shown.

LEWIS B. SIMON.
